To all whom it may concern:

Be it known that I, JOHN DEAN, a citizen of the United States, residing at Racine, Racine county, State of Wisconsin, have invented a certain new and useful Design for Bridle-Bit Mouth-Bars; and I do hereby declare the following to be a full, clear, and exact description of the invention, such as will enable others skilled in the art to which it appertains to make and use the same.

This invention relates to a certain new and useful design for bridle-bit mouth-bars.

The object of the invention is to produce an exceedingly effective and artistic design for bridle-bit mouth-bars which will possess certain striking or distinguishing features in shape or contour.

My invention consists in the design for a bridle-bit mouth-bar, substantially as set forth hereinafter and shown in the accompanying drawings.

In the accompanying drawings, Figure 1 is a perspective view of the mouth-bar. Fig. 2 is a side elevation thereof. Fig. 3 is an end elevation thereof.

My bridle-bit mouth-bar consists of the approximately round or cylindrical bar a, having the annular end grooves bb, each groove being formed around the bar end by the two annular exterior enlargements or flanges cc, 30 substantially as shown in the accompanying drawings, whereby said grooves are located at the extremities of the bar except for the outer enlargements c, said grooves each having a rounded floor and flaring outwardly, said 35 outer enlargements forming the extremities of the bar and having imperforate convexed outer faces.

Having thus fully described my invention, what I claim as new, and desire to secure by 40 Letters Patent of the United States, is—

The design for a bridle-bit mouth-bar, substantially as shown and described.

In testimony whereof I affix my signature in presence of two witnesses.
